CLAIM

The ornamental design for flexible hanging storage unit, as shown and described.

DESCRIPTION

FIG. 1 is a front elevational view of a flexible hanging storage unit showing my new design;
FIG. 2 is a rear elevational view thereof;
FIG. 3 is a side elevational view thereof, the side opposite being a mirror image of that shown;
FIG. 4 is an enlarged fragmentary front elevational view of the top-most portion thereof; and,
FIG. 5 is an enlarged fragmentary front elevational view of the top-most, left side connection thereof.
